BEVERAGE COASTER

Charles R. Johnson, San Antonio, Tex.

Application December 26, 1956, Serial No. 630,655

4 Claims. (Cl. 215—100.5)

This invention relates to coasters for beverage glasses.

It is an object of the present invention to provide an improved coaster for beverage glasses or bottles which will absorb moisture that is "sweated" from the bottom of the glass when used for iced beverages and which will remain on the glass until released.

It is another object of the present invention to provide a beverage coaster of the above type which includes an absorbent base member and a pair of oppositely disposed resilient clamps vertically spaced thereabove which are adapted to engage the sides of the glass or bottle and which are connected to the absorbent base member.

Other objects of the invention are to provide a beverage coaster bearing the above objects in mind which is of simple construction, has a minimum number of parts, is inexpensive to manufacture and efficient in use.

For other objects and for a better understanding of the invention, reference may be had to the following detailed description taken in connection with the accompanying drawing, in which:

Figure 1 is a top perspective view of a preferred embodiment of the present invention shown alone;

Fig. 2 is a top plan view in exploded relationship of the parts comprising the invention;

Fig. 3 is a vertical sectional view taken along the line 3—3 of Fig. 1, and showing in dotted outline the position of the glass on the coaster; and

Fig. 4 is a fragmentary rear elevational view of the central portion of the coaster.

Referring now more in detail to the drawing, 10 represents a circular resilient wire, the ends of which are slightly spaced apart (Fig. 4) and are integrally formed with the inwardly and upwardly extending straight portions 11 which diverge upwardly away from each other. The upper ends of the portions 11 are each integrally formed with the oppositely disposed complementary wire jaws 12 which represent segments of an ellipse and which are closer together than the outside diameter of the drinking glass 13 at the point at which they engage the same, so as to insure resilient tensile engagement therebetween.

A pair of upper and lower absorbent discs 13' and 14 of slightly greater diameter than the diameter of the base wire 10 are suitably secured thereto, as shown in Figs. 3 and 4. The diameter of the absorbent discs 13' and 14 is also slightly greater than the bottom of the bottle or beverage glass 13 which rests thereon. Thus, the wire base 10 serves as a stiffening member for the vertically spaced absorbent discs 13' and 14 and also serves to connect the same fixedly to the clamps 12 which engage the glass.

The wire portion 10, 11, 12 of the invention may be formed of resilient metal, plastic or other substance having similar physical characteristics and the jaw portions 12 may be covered with rubber to increase their frictional properties.

The peripheries of the absorbent discs 13' and 14 extend outwardly beyond the wire base 10 sufficiently to permit them to be secured together by means of the stitching 15 or other suitable securing means, for example glue.

The spring tension of the expanded jaws 12 will retain

2

the coaster on the glass or bottle 13 until it is desired to remove the same, and will prevent it from becoming separated therefrom.

As shown in Fig. 3, the free ends of the base ring 10 are bent outwardly and upwardly in the curved portion 16 before joining the straight portions 11, to provide clearance for the peripheral edge of the uppermost absorbent disc 13', as will be obvious. The straight portions 12 are bent inwardly sufficiently so that their upper ends are aligned vertically with the free ends of the base ring 10. This construction prevents the bottom rim of the glass or container from being placed somewhat off the coaster pad. It will be noted that the jaws 12 are oval rather than round in shape so that all size glasses or containers will center themselves on the pads 13', 14. Were the jaws round, they would cause a small glass or container to abut the straight portions 11, thereby leaving the glass or container off center from the pad.

The flexible pads 13' and 14 may be designed so that they may be removed from the base 10 for cleaning. For example, they may be made as inserts of circular shape having a recessed peripheral groove around the center of the edge of the periphery of the pad which would receive the base ring therewith in resilient engagement. Such a case, a unitary pad would be provided and could be snapped into and out of engagement with the base wire 10. The lips of the pad override the rim of the coaster base 10 on top and bottom, which keeps the pad in place. The pads may be designed from sponge rubber, cellular material or other absorbent materials.

While various changes may be made in the detail construction, it shall be understood that such changes shall be within the spirit and scope of the present invention as defined by the appended claims.

35 What I claim as new and desire to protect by Letters Patent of the United States is:

1. A beverage coaster comprising a circular wire of resilient material having the free ends thereof slightly spaced apart, said free ends being integrally formed with upwardly and inwardly extending portions, each of said upwardly and inwardly extending portions at the upper ends thereof being integrally formed with an oval shaped wire jaw extending forwardly thereof adapted to engage one side of the glass or the like and providing a pair of oppositely disposed complementary engaging jaws, absorbent pad means of substantially circular shape and of greater diameter than said circular wire, and means for securing said absorbent pad means to said circular wire whereby to retain the absorbent pad means in engagement with the bottom of the glass or the like by the resilient engagement therewith of said resilient jaws thereabove.

2. A beverage coaster according to claim 1, said absorbent pad means comprising substantially circular upper and lower pads of greater diameter than the wire base and positioned on the upper and lower sides thereof, and means for securing said upper and lower pads together around their peripheries with the wire base therebetween.

3. A beverage coaster according to claim 1, said absorbent pad means comprising a unitary flexible circular pad of greater diameter than said wire base, said pad around its periphery having an annular groove receiving said circular base wire resiliently therewithin, whereby to permit the removal of the pad for cleaning.

4. A beverage coaster according to claim 1, said base wire being bent outwardly and upwardly before joining said inwardly and upwardly extending portions to provide clearance for the periphery of the absorbent pad means.
